CLAIM

The ornamental design for a luggage panel, as shown and described.

DESCRIPTION

FIG. 1 is a front perspective view of a luggage panel showing our new design;

FIG. 2 is a front elevational view thereof;

FIG. 3 is a right side elevational view thereof;

FIG. 4 is a left side elevational view thereof;

FIG. 5 is a top plan view thereof; and,

FIG. 6 is a bottom plan view thereof.

In the above-described drawing figures, the broken lines immediately adjacent the shaded areas represent the bounds of the claimed design, while all other broken lines are directed to environment and are for illustrative purposes only; the broken lines form no part of the claimed design. Additionally, the rear face of the luggage panel is flat and contains no surface ornamentation.
